UNITED STATES PATENT OFFICE.

KNUD OSCAR WILLADSEN, OF ASTORIA, NEW YORK.

BARREL-BUNG EXTRACTOR.

Application filed December 10, 1925. Serial No. 74,502.

The main object of this invention is to provide a device for extracting bungs from barrels which are more or less securely fixed in place. The usual method of removing 5 a bung fixed in a barrel is to jar the bung loose with a hammer until it is easily removed, and when this is not feasible, wedges such as chisels are inserted between the bung and hole and a prying leverage is 10 exerted on said chisel wedges to loosen the fit of the bung for its easy extraction. In the majority of cases, chisels must be employed and when they are, the surface of the bung hole is marred and damaged so 15 that a succeeding bung will not fit into place in a leak-proof manner. This invention is designed to eliminate these features by providing a lever and a screw arrangement which cooperate in extracting a bung in 20 such manner so nothing but a bung is damaged, it being customary to use new bungs at successive sealings of a barrel or container.

The above and other objects will become 25 apparent in the description below, in which characters of reference refer to like-named parts in the drawing.

Referring briefly to the drawing, Figure 1 is a partially sectioned elevational view of 30 a barrel, showing the application of the bung extractor.

Figure 2 is a side elevational view of the bung extractor.

Figure 3 is a sectional plan view, taken 35 on line 3—3 of Figure 2.

Figure 4 is an elevational view of the chisel.

Referring in detail to the drawing, the 40 numeral 10 indicates the ends of a barrel. These ends are encircled by staves 11 which are held in place by hoops 12. One of these staves 13 is provided with the usual tapered bung hole into which a bung 14 is adapted to be secured when sealing the chamber 15 45 in the barrel. The Figures 2 and 3 of the drawing illustrate a device for extracting these bungs from the bung holes of the barrel without damaging the bore of the bung hole. Said device consists of a base plate 16 50 in which an axial relatively large opening 17 is provided. A plurality of posts 18 project upwardly from the upper face of the base plate 16 and are surmounted by a cover flange 19 which has openings 20 55 therein. These posts are rectangular in cross section and form guides for a sliding

carriage. The sliding carriage comprises a plate having arms 21 extending outwardly from an axis at angles which are separated by 90 degrees. The arms 21 are provided 60 with recesses 22 which register and are in sliding contact with the surfaces of the post 18, which latter guide the carriage in its vertical movement between the cover flange 19 and the base plate 16. The arms are 65 further provided with inclined surfaces 23 in which radiating channels 24 are formed. In these channels, the heads of wedge chisels 25 are slidably mounted. The wedge chisels are provided at their upper end with ledges 70 26 and grooves 27, and additional lower ledges 28, and have a knife edge 29 at their lower ends. These chisels are slidable in the channels 24 and describe a radial pathway toward the axis of the plate forming 75 part of the arms 21. At a point near the intersection of these arms 21, a pair of lifting studs 30 are mounted. These studs are provided with flanges 31 which are adapted 80 to be engaged by a bifurcated lever 32 which is pivoted on a pin 33, the latter being anchored in a block 34. A stud 35 is slidably mounted in the cover flange and extends vertically. This stud has a decreased diameter which serves as a shank 85 36, said shank being surmounted by a handle 37. The lower end of the stud 35 passes thru an opening in the plate having arms 21 and at its lower end, has a conical tip 38 fashioned as a wood screw and is rigid 90 with the stud 35. A bar 39 is formed integral with the block 34 and extends outwardly from said block beneath the bifurcated lever 32.

In using the device for extracting bungs, 95 the device is placed over a bung hole from which the bung is to be removed. These bungs usually fit securely and tightly into the hole. To loosen the frictional contact between the bung and bung hole, the outer free end of the bifurcated lever is lifted. The lever being fulcrumed on the pin 33, rotates the bifurcated end downwardly and lowers the arms 21 attached to the plate. Before manipulating the lever 32, the chisels 100 25 are adjusted within their channels 24 to such position that they will comfortably fit around the bung 40 at four different positions, which positions being 90 degrees from the other. The bifurcated end of the lever 32 is then lowered thus urging the arms 21 downwardly to cause the chisels 105 25

to wedge themselves between the bung and bung hole. When in this position, the stud 35 is lowered manually and the handle 37 is rotated so that the screw tip 38 engages the material of the bung, which is commonly wood, and in this manner, secures itself thereto. The handle 37 is then manually lifted, after the lever 32 has been lifted, and after the chisels 25 have partly 10 pried the bung 40 loose from the bung hole, the stud 35 easily lifts the bung out of place from the bung hole.

I claim:—

1. A bung extractor comprising a floating 15 plate, chisels adjustably secured to said floating plate, a frame guiding said floating plate, a lever adapted to lift or lower said floating plate, said chisels being adapted to be pried between the bung and 20 bung hole, and a stud adapted to engage said bung and lift the latter from place.
2. A bung extractor comprising a frame, a floating plate slidable in said frame, inclined arms on said plate, adjustable chisels 25 mounted on said arms and adapted to engage between the bung and the bung hole, and means for extracting a bung from a bung hole.
3. A bung extractor comprising a frame, 30 a floating plate slidable in said frame, inclined arms on said plate, adjustable chisels

mounted on said arms and adapted to engage between the bung and the bung hole, means for lifting said floating plate comprising a bifurcated lever pivoted on said frame, flanged studs rigid on said floating plate engaging the lever and a bar rigid with said frame beneath the lever adapted to cooperate with the lever for rotating the same upwardly, a stud slidably mounted in 40 said frame, a screw tip on said stud at its lower end engageable with the bung.

4. A bung extractor comprising a frame, a floating plate slidable in said frame, inclined arms on said plate, adjustable chisels 45 mounted on said arms and adapted to engage between the bung and the bung hole, channels extending radially on said plate, said chisels being slidably mounted in said channels, means for lifting said floating 50 plate comprising a bifurcated lever pivoted on said frame, flanged studs rigid on said floating plate engaging the lever and a bar rigid with said frame beneath the lever adapted to cooperate with the lever for rotating the same upwardly, a stud slidably mounted in said frame, a screw tip on said 55 stud at its lower end engageable with the bung.

In testimony whereof I affix my signature.

KNUD OSCAR WILLADSEN.
